UNITED STATES PATENT OFFICE.

WALTER E. DERWENT, OF BELVIDERE, ILLINOIS, ASSIGNOR TO NATIONAL SEWING MACHINE COMPANY, OF BELVIDERE, ILLINOIS, A CORPORATION OF ILLINOIS.

DESIGN FOR A DROPOHEAD SEWING-MACHINE CABINET.

Application filed February 23, 1922. Serial No. 831. Term of patent 14 years.

To all whom it may concern:

Be it known that I, WALTER E. DERWENT, a citizen of the United States, residing at Belvidere, in the county of Boone and State of Illinois, have invented a new, original, and ornamental Design for Drophead Sewing-Machine Cabinets, of which the following is a specification, reference being had to the accompanying drawings, which form a part of this specification.

The figure is a perspective view of a drophead sewing machine cabinet, showing my new design.

I claim:

The ornamental design for a drophead sewing machine cabinet, as shown.

In testimony that I claim the foregoing as my invention I affix my signature in the presence of two witnesses, this 16th day of February, 1922.

WALTER E. DERWENT.

Witnesses:
